UNITED STATES PATENT OFFICE

159,701

COMBINED CLOCK AND RADIO OR THE LIKE

Russell Joseph Viani, New York, N. Y.

Application September 29, 1949, Serial No. 5,207

Term of patent 14 years

(Cl. D56—4)

To all whom it may concern:

Be it known that I, Russell J. Viani, a citizen of the United States of America, residing at New York, in the county of Bronx and State of New York, have invented a new, original, and ornamental Design for a Combined Clock and Radio or the like, of which the following is a specification, reference being had to the accompanying drawing, forming part thereof.

Fig. 1 is a front perspective view of a combined clock and radio or the like, embodying my new design.

Fig. 2 is an end elevation of the same.

I claim:

The ornamental design for a combined clock and radio or the like, substantially as shown.

RUSSELL JOSEPH VIANI.
